Felix Fossard, Philadelphia

Letter and Patent

The Schedule referred to in these Letters Patent, and making part of the same containing a description in the words of the said Felix Fossard himself of his improvement in the process of dying and in manufacturing the products of Potash and Soda.

To all whom it may concern. Be it known that I, Felix Fossard, of the City of Philadelphia in the State of Pennsylvania have invented and secured certain improvements in the mode of manufacturing the Products of Potash and Soda and of dying therewith and with certain other materials herein named. The processes described and claimed as being improvements, are those specifically described by me in the two several patents heretofore granted to me by the government of the United States, to wit, one on the fourteenth day of December 1832, and one on the 23rd day of April 1834. and I do hereby declare that although there are certain processes and machinery known as herein described which have been used and known before, I do not intend to claim them as my invention in the patent which I have hereby obtained, but have introduced them with a view to render the processes that I do claim perfectly clear and intelligible to those skillful in the art to which they appertain. Referring thereto not only to the description herein given but also to the specifications contained in my former patents, for a full understanding of the subject. I limit the claims made to the following items. I claim the improved process of dying bluish by the double decomposition of a soluble copperous reagent and a salt of iron or other metal by the means hereinafter recited. - Process of Dying in Blue Acid Bath, No. 1. This Bath is prepared with 100 parts of water in weight to one part of sulphuric or other suitable acid and is to be employed at 80 to 100 degrees of heat. It is to be always composed of an acid and

after the woolen material has passed through it. Washing with the
2. consists of water to be used either at the ordinary temperature or
warmer and its use is only recommended for economy's sake to wash off
the excess of acid which may remain on the woolen material on being withdrawn
from Bath No 1. - Bath No 3. prepared with water
and a small quantity of alkali but in preference to others with the same
rate of Soda (viz one part and a quarter of alkali in weight to 100 parts
of water heated to 75 or 80 degrees Fahr.)

Prissate Bath. No 4. Is prepared with the following proportion of
Potash (any other ferruginous Prissate will answer the same purpose) and
should be 3 degrees stronger. becomes ammonia for salts and employed
at about 90 to 100 degrees Fahr. as this Bath should always be
kept in an acid state in preference to an alkaline one, one pound of sul-
furic acid may be added to every 350 gallons of water of ferruginous
bath No 5. To be formed with a potash of iron and water (any
other salt of iron, Molybdenite, &c., may be used with success) enough
and to make about 1/4 degree of ammonia acetate and should be em-
ployed at about 100 or 70 Fahr. This Bath may be acidulated like No
4 or be used in its neutral state. - Bath No 6. Consists of
water heated to about 100 or 110 degrees Fahr. to which should be ad-
ded a small quantity of acid say as in No 4.

Bath No 7. Consists of water heated to about 100 degrees Fahr. to which
should be added 1/2 part acid in weight to 100 parts of water. The liquid
which drains from the material coated upon on being withdrawn from
this Bath should always be of an acid taste.

Steel Bath. No 8. Is employed without immersing the dyed material
in a liquid. It consists of a steel made closed and heated to about 100
degrees Fahr. in which the dyed material is to be placed and this place
should be covered with a woollen cloth at the top in order that the heat
may pass off. - Ammonical bath No 9. It is composed of an
Ammonical bath as follows. A close plumbings of iron as follows. The dyed stuff
is to be hung up and some highly concentrated liquid Ammonia is
to be placed in a vessel on the ground. Ammonical gas may also be
used.

produced in any other convenient way. The vapour rising from the ammonia will have an instantaneous effect and produce a darker colour. The liquid ammonia may also be used in another form mainly fit as much of it in water as may be necessary to produce the desired colour and pass the material regularly through it. Practice alone can dictate the quantity and the quality of the ammonia both as that of the water employed may differ. This bath is to be used at the ordinary temperature or heated to 60 or 70 degrees Fst.

Bath No. 1 will be useful for about 20 operations. No 2 for 5. No 3. for 10. No 4 for 100. No 5 for 50 No. 6. for 4. No 7 for 7. No 9 for as long as any of the ammoniacal gas remains. The Baths No 1. 2. 3. 4. 5. 7. 4. 9. requiring kept in the order indicated by adding from time to time the various things, with which they are formed. When the baths No. 4 and 5 are no longer fit for use they may be mixed together in equal volume and sufficient Number made with the deposit. The vessel containing the Bath, intended for dyeing in the piece should be an oblong square form and those for dyeing wool of a round form furnished with a strainer worked by means of a crane and with a frame to hold the strainer on the heat while the wool is draining. Skins are worked in the ordinary way. The Baths No. 4 & 5 should be heated by steam in contact and not condensed. For woolens in the piece the cloth or stuff being freed from grease and fullled whether the last operation is necessary, it should be passed through the baths No. 1. 2. and 3. in any ordinary sort of vessels and by the means ordinarily employed by dyers. After the Bath No. 3. should be strained and cleaned with fuller's earth and be well washed in plenty of cold water. The cloth being well drained (or dried in preference) pass it slowly through Baths No. 4. 5. 6 and 7. by means of the apparatus represented in the plate accompanying these specifications and detailed below. The stuff should be passed 4 or 5 times, alternately, from Bath No. 6 to Bath No. 7. and vice versa for the purpose of raising the colour or fixing the shade of iron, after this, if the intensity of colour desired is not obtained it must be re-heated through the Baths No. 4. 5. 6 & 7. as recommended until the desired colour is obtained.

after which the cloth should be soaked and cleaned with fullers earth and be washed with cold water. Then dry the cloth on ^{hot} ~~hot~~ ^{hot} towels and place it on ^{hot} ~~hot~~ ^{hot} tumbulators in the Stone Bath No. 8. for about 3 hours and if desired let it afterwards be submitted to the action of Ammonia in the bath No. 9 or be passed through a liquid ammonia bath. The application of ammonia is only resorted to in certain cases when particular colours are wanted, but more so where a species of Meddy is desired.

The operation may be shortened by raising the wool by means of the baths No. 1. and 3. washing it and working it into cloth. This cloth having been wound upon a roller in the finishing room is carried to the dye house and passed through the baths 4. 5. 6 and 7. Then it is to be soaked and cleaned with a mixture of fullers earth and of white soap water cold and concentrated as experience will dictate. It will be necessary to take care that the soap employed is not too caustick and that it is perfectly dissolved before it is applied and that the cloth (if it has been dried after the dyeing) is rendered little humid before the soap is added. If however it should happen that the soap renders the colour less brilliant let the cloth be submitted to the action or contact of steam and it will become quite fresh again then dry and finish the cloth. When light blues are wanted baths No. 4. 4. 5 should be made weaker or the bath No. 9 as well as it, substitute the white soap water should be suspended with. Description of the apparatus. A tank in which the baths are formed. B. blocks to draw off the contents of the bath to roller on which the cloth is wound before entering the bath. C. rollers over and under which the cloth passes in bath D. equalizing and pressing the liquid out of the cloth. These rollers should be covered with coarse cloth &c. E. Roller. F. pressing Rollers done as E. - H. Rollers the first one to guide the cloth into the bath and two others one to pass it regularly through the liquid with the cloth may be wound on this last one previously to ascending into the air. G. Rollers of roller on which the cloth may be wound or it may be drawn out of the bath at liberty. H. membrane which should be fastened off at the top and bottom.

to the same proportion as the Bath No 6 & 7. This is not absolutely necessary but it is recommended. I guiding Rollers & M. Tubes introduced into the bath for heating them by steam. A tube for heating and another to convey to receive the cloth after it is dyed. P. Guiding Rollers to conduct the cloth into the carriage C. The system of Rollers is represented in the plate unconnected with particularly the passing Valley which should be made very true and flexible but they are not absolutely necessary. Any other means may be resorted to by which the distribution of the liquid on and through the tissue in an even and regular way shall be obtained. It will also have to understand, I lay no claim to any part of the apparatus above described. The operation for wool is as follows take wool which has been well cleaned by the ordinary process, put it into Bath No 1 for about 10 minutes then raise it out of the liquid, let it drain for 10 minutes, lower it again and let it remain 10 minutes, then raise it and allow it to drain off for 10 or 15 minutes and pass it into bath No 2 and 3 observing the same rules as before, having the same plan for each of these baths as for No 1. Then have the wool washed the usual way, when it is well cleaned (or dry-cleaned before dyeing) place it again into a strainer and carry it to bath No 4 which should be located in the manner as in bath No 1 and after the last immersion it should be allowed to drain for 10 minutes suspended to the crane. Then it should be lowered on the frame, placed across the bath and a false cover, pierced with holes, should be placed on. Turn then the strainer and wool upside down and allow them to remain in that position for 10 minutes. This operation being intended to distribute the liquor as equally as possible on every part of the wool. Then turn the strainer endwise to its original position and pass it promptly to bath No 5 when it should occasionally be raised and lowered for about 1/4 of an hour. Then pass it just above the bath and allow it to drain for about 30 minutes then pass it into bath No 6 where the immersion is should be made similar to those in regard to bath No 1 after which pass it into bath No 7 where the immersion time should be 15 minutes will be sufficient. Wool is plenty of saturated

dry by the ordinary way and then place the wool into the slow bath No 8. for about 3 $\frac{1}{2}$ of an hour. This will complete the operation of drying and the wool may be treated as though dyed by any other process. The observations relating to the dying in the piece inserted above apply also to the dying also in the wool. another method for dying wool for Broadclothes by this new process, is to pass it into bath No 1 and then to scour it in the ordinary way and wash in plenty of water. when drained pass it into a bath of carbonate of Soda, making about 2 degrees of the ammonia of Beaumes for salts and 120 degrees. Sit for about 10 minutes when drained carry it to bath 3. for about 20 minutes, wash immediately in plenty of water or rather lower the spout when the wool will have been draining for but a few minutes into a vat full of lukewarm water so that the liquid draining from the wool be not allowed to become acid again by absorption of oxygen for in that state it combines anew with the iron and comes off from the wool. Then dry. the advantage of this method is that at the stages of the process the material may be dyed in many colours (and especially in black) by means of dye woods, without addition of metallic salts to the baths and with a great saving of dye stuffs. For blue the yellow wool is washed into cloth full of soap &c. then the piece is passed into baths No 4, 6 and 7 by means of the apparatus described above. If the bath headings be one of a dye solid to acids they will be faithfully preserved and the cloth will bear the appearance of having been dyed all together in the wool. carry to the stocks for cleaning &c. - There are several other modifications of this process which will occur to the dyer and be useful to him in various cases. Clothy stuffs &c. dyed in presence of iron may be dyed in fancy colours by the ordinary process and dye stuffs as when dyed in the dye blue for colouring it as necessary in order to obtain evenness and uniformity of colour to distribute the liquid equally after bath No 4 & 5 by squeezing them with sticks and if suspended by changing their position that is to say by turning the upper part down and vice versa as long as thought proper. any other sort of tissue cloths or skins than wool in only do not require bathes Nos 1, 2, 3 only silk requires to be freed from the gum they contain by any of the ordinary

process. The object of this improved process for which a Patent has been granted to me by the government of the United States on the 23rd of April 1834 is to enable the manufacturer to produce a much finer product of Potash than those generally found in the market and therefore more available in the dryings process, and also to produce it in much larger quantities at a time with comparatively much less expense and trouble to himself, and convenience to the neighbourhood.
